T. S. CASNER

RELAY

Filed April 23, 1925

FIG. 1.

FIG. 2.

Inventor

T. S. Casner,
By Watson, Cort, Morse
& Grindle. Attorney

UNITED STATES PATENT OFFICE.

THADDEUS STEPHENS CASNER, OF PLAINFIELD, NEW JERSEY, ASSIGNOR TO RADIO ELECTRIC CLOCK CORPORATION, OF NEW YORK, N. Y., A CORPORATION OF NEW JERSEY.

RELAY.

Application filed April 28, 1925. Serial No. 25,390.

This invention relates to electrical relays, and relates more particularly to relays of high sensitivity which are adapted to be operated by relatively weak electrical impulses 5 to open and close a local circuit of considerable magnitude.

In certain types of mechanism it is highly desirable to have a relay which may be used with a radio receiving set to open and close 10 a local circuit in accordance with signals received from a distant transmitting station. In my co-pending application, Serial No. 455,262, filed March 24, 1921, an apparatus is disclosed for automatically setting the 15 hands of a clock in accordance with radio telegraph time signals received, for example, from the Government station at Arlington, Virginia. This apparatus includes an electro-mechanical mechanism for adjusting the 20 clock hands, a radio receiving set, and a relay operatively connecting these two sections of the apparatus. The relay herein disclosed is particularly applicable for use 25 in such a combination, but is not limited in this respect, being of general application and capable of being used in all circumstances where it is desirable to have a relay which becomes operative upon the receipt of very faint current impulses.

30 The electrical impulses set up in the antenna circuit of a receiving station by the Hertzian waves emanating from a transmitting station, are very weak, and although greatly amplified by the receiving apparatus, the resulting current in the telephone 35 circuit of the average radio receiver is still of a low order of magnitude, and is not sufficiently strong to operate a relay of any of the ordinary types.

40 The primary object of this invention is to provide a relay adapted to be operated by weak electrical impulses to open and close a local circuit.

45 A further object of my invention is to provide a relay adapted to be used in connection with a radio receiving set to open and close a local circuit in accordance with signals received from a distant transmitting station.

50 Other objects and advantages of my invention will be apparent from the following description, taken in conjunction with the

accompanying drawings, which form a part of this specification, and in which:

Figure 1 is a side elevation of a relay according to my invention; and

Figure 2 is a front elevation of the same.

Referring more particularly to the drawings, in which like reference characters denote like parts throughout the several views 60 thereof, 10 denotes a base or support of insulating material upon which is mounted a telephone receiver 11 by means of a bracket 12. The bracket 12 is secured to the base 10 and has a vertical portion to which 65 is fastened the back of the telephone receiver 11. The upper part of the bracket is then bent forwardly and downwardly so as to terminate in front of the diaphragm of the receiver. This end of the bracket 12 70 is provided with a slot 13 which forms a bearing for the knife edge of a lever 14. The bracket 12 may be cut out of heavy sheet metal and bent to the shape shown. The telephone receiver is of well-known type, and 75 may be, for example, a Brandes receiver.

The lever 14 is made of bamboo or other light material, and is pivoted at 15 to an extension 16 secured to the center of the diaphragm 17 of the receiver 11. The lower 80 end of the lever 14 projects between two leaf springs or blades 18 which are secured to the base 10 and carry contacts 19. These contacts may be utilized to control a local circuit.

85 The telephone receiver 11 is connected to a radio receiving set of any suitable or desired type in the usual manner. Upon passage of radio frequency electrical impulses through the circuit to which the receiver is connected, the diaphragm 17 will be caused to vibrate at an audio frequency corresponding to the division of the radio frequency impulses into groups. These vibrations will be transmitted to the lever 14 which will thus be caused to vibrate rapidly about the pivot 13. The lower end of the lever 14 has a considerably larger amplitude of vibration than the diaphragm 17, and consequently the blades 18 will be forced apart by the vibration of the lever, thus separating the contacts 19 and opening the local circuit.

100 In order that the contacts 19 may be kept separated during the entire time that the

diaphragm 17 is vibrating, it is essential that the blades 18 have a natural frequency of vibration considerably different from the frequency of the audio frequency electric impulses in the telephone receiver circuit, which, of course, govern the frequency of vibration of the diaphragm 17 and lever 14. Preferably, the natural frequency of vibration of the blades 18 should be about half the frequency of the telephone current. Since the telephone current of a radio receiving set usually has a frequency of about 500 cycles per second, the blades 18 are conveniently made of such weight and stiffness that they will have a natural frequency of 250 vibrations per second. It is obvious that the free vibration rate of the blades 18 may be changed in accordance with the pitch of the controlling signal to be received.

20 The frequency of vibration of the lever 14 being much greater than that of the blades 18, the lever will push one blade to one side and then the second blade to the other side, and then meet the first blade on its first return vibration and hold it from completing this vibration, and the same thing occurs with the second blade, with the result that the blades and the contacts 19 are effectively separated as long as the lever continues to vibrate.

25 This relay is simple in construction and yet operates very efficiently and with great freedom from troublesome adjustments. Many changes or alterations might be made in the structure above described without departing from the spirit of my invention, and I therefore desire to be limited only by the prior art and the scope of the appended claims.

30 Having thus described my invention, what I claim as new and desire to secure by Letters Patent is:

1. In a relay of the class described, in combination, a vibratory diaphragm, a pair of flexible contact carrying members normally in mutual engagement, a pivoted lever disposed between said members and connected to said diaphragm so as to strike

the members in alternation to keep them separated due to their inertia during vibration of the diaphragm.

2. In a relay of the class described, in combination, a vibratory diaphragm, a lever pivotally supported at one end adjacent said diaphragm and parallel thereto, a connection between the center of said diaphragm and said lever, whereby the amplitude of vibration of the free end of said lever is greater than that of said diaphragm, a pair of flexible blades positioned with their free ends on either side of the free end of said lever, and contacts mounted on said blades and adapted to be separated by alternate outward blows of the lever during vibration of the diaphragm.

3. In a relay of the class described, in combination, a base, a telephone receiver secured to a bracket on said base with its diaphragm in vertical position, a downwardly directed bearing surface mounted in front of said diaphragm, a lever having its upper end pivoted on said surface, an operative connection between said lever and said diaphragm, a pair of flexible blades secured to said base and having their free ends embracing the free lower end of said lever, and a contact mounted on each of said blades near the free end thereof and adapted to be separated by alternate outward blows of the lever during vibration of the diaphragm.

4. In a relay of the class described, in combination, a vibratory diaphragm, a lever pivotally supported adjacent said diaphragm, a connection between said diaphragm and said lever whereby the amplitude of vibration of the free end of said lever is greater than that of said diaphragm, a pair of flexible blades embracing the free end of said lever, said blades having a natural frequency of vibration substantially less than the normal frequency of vibration of said diaphragm, and a pair of contacts mounted on said blades.

In testimony whereof I hereunto affix my signature.

THADDEUS STEPHENS CASNER.
